Original application September 7, 1934, Serial
No. 743,044. Divided and this application
July 31, 1935, Serial No. 34,020

17 Claims. (Cl. 235—60)

This invention relates to adding machines and more specifically to the type controlled by ten digit keys.

This application is a division of the application of F. L. Fuller and S. Brand, Serial No. 743,044, filed September 7, 1934 for Combined record sorting and accounting machines.

The main object of the present invention is to devise a ten-key adding machine which is simple in construction, reliable in operation and which requires a minimum of expenditure of manual power.

The present machine is provided with a series of item set-up wheels which are successively set up as the keys are operated. By means of a power-operated mechanism the differential set-up of these wheels is conveyed to a set of printing elements or to totalizer elements. With the exception of the specific form of mechanism hereinafter employed this form of mechanism is old and well known in the art. The present machine includes particularly improved constructions whereby the set-up wheels are successively set up as the keys are operated in a manner that requires a minimum expenditure of manual power.

The item wheels are successively set up by means of a master wheel which is operated by a power drive through a friction drive, the source of power being preferably the same power drive that causes the differential setting of the totalizer or printing elements.

The differential position of the master wheel is controlled by a digit set-up mechanism which consists of a rotary drum provided with a series of longitudinally shiftable pins or digit stops, one of which is in shifted position to normally prevent rotation of the master wheel by the friction drive.

The selection of and the positive shifting of these digit stops are effected by electrical means under control of the keys, the depression of a key causing the energization of a related magnet which shifts the associated digit stop.

The keys are adapted to be successively depressed to set up the item wheels. To eliminate manual power in operating controlling devices usually operated by these keys electrical-power-operated devices are provided in the present machine. Such an arrangement insures that incidental operations, such as, the release of the master wheel for rotation, the escapement of the item wheels, the energization and deenergization of controlling magnets, etc., will always take place independent of manual power and which in prior constructions was a decided ob-

jection since a key was depressed with difficulty and it could be returned before its stroke was completed to effect the incidental operations.

Each key when manually depressed a slight extent operates a member which closes associated contacts of the circuit of the magnet that shifts a digit stop. By common control means each key closes a set of main control contacts which causes the energization of the digit stop shifting magnet and a supplemental electro-magnet. The latter causes a coupling device to complete the operation of the member and also releases the digit stop carrying drum for rotation. The master wheel rotates with the drum until the shifted digit stop stops its rotation. Subsequently, when the first item wheel is set up an escapement mechanism operated by the supplemental electro-magnet causes the master wheel to engage the next item wheel, and thereafter all electrical circuits are opened for their normal condition.

By the construction just described a very slight and light key touch is provided and the item may be set up on the wheels by a rapid and light depression of the keys. The correctness of the set-up operation may be verified by a visual reading of numerals on the item wheels.

A still further object of the present invention is to provide an error key with improved controlling mechanism whereby an incorrect item set-up on the item wheels may be erased without transmittal of the amount to the totalizer or printing elements.

A further object of the present invention is the provision of a key-release-key for manually releasing the locked down error key.

Other objects and advantages will appear from the following specification and drawings in which drawings:—

Fig. 1 is a sectional view of the ten-key mechanism and part of the electrical controlling mechanism.

Fig. 2 is another sectional view of the ten-key mechanism showing particularly the electrical coupling mechanism and electrical contact devices.

Fig. 3 is a plan view, greatly reduced, showing the keyboard arrangement.

Fig. 4 is a top plan view of the item entering mechanism and the ten-key controlling mechanism.

Fig. 5 is a detail view of the device for shifting the set-up wheels when amounts are successively set thereon.

Fig. 6 is a detail view in side elevation of the

item set-up wheels, the rack engaging mechanism for the item wheels and the error key mechanism.

Fig. 7 is a view in front elevation showing a part of the ten-key set-up mechanism and the means for driving the master wheel for the set-up wheels.

Fig. 8 is a detail view of the set-up mechanism and the means for restoring the set-up wheels to home or normal positions.

Fig. 9 illustrates the preferred form of one revolution clutch mechanism.

Fig. 10 is an electrical wiring diagram of the machine.

Fig. 11 is a view of part of the printing mechanism and totalizing mechanism.

Fig. 12 is a detail view of the key-release mechanism.

Framework

The various mechanisms are carried by a suitable base (not shown) and parallel side frames 117 and 118 (Fig. 4) which primarily carry the ten-key controlling mechanism. The item set-up mechanism and item entering mechanism are carried by the frame plates 31 and 32.

Amount set-up mechanism

To enter an item the operator sets up the amount to be entered on the ten-key amount set-up mechanism which includes the keys 110 (Figs. 1, 2, and 3). Depression of any of these keys operates mechanism now to be described in identically the same manner and effects a differential rotation of a master wheel to set amounts corresponding in digital value to the particular keys depressed on corresponding set-up wheels, which amounts are later transferred to a rack system to operate the totalizers or to set up printing elements.

Since the operation of each of the keys is exactly the same, a description will be given of the operation of the set-up mechanism upon depression of only one of the said keys, for example, the "6" key.

As is shown in Figs. 1 and 2, the bifurcated lower ends of the key stems 111 of the keys 110 each embrace a stud 120 on a pivoted arm 121, there being an arm 121 associated with each key 110. The arms 121 are urged upwardly against a stop rod 465 by individual springs 466 set in a cross bar 467 which bar is also slotted to guide the arms 121. Pivoted on the stud 120 is a latch 468 having a cam slot 469 therein embracing a rod 470 supported on projections of the cross bar 467.

The first downward movement of the depressed key cams the latch 468 counterclockwise to engage the shoulder end thereof beneath an angular bail 476 underlying all the arms 121 and carried by arms 477 and 478 (see also Fig. 4) pivoted on the shaft 122. The arm 478 (Fig. 2) extends upwardly and a spring 479 stretched between a stud 480 on said arm and an arm 481 pivoted on a shaft 122 normally holds a shoulder 480a of the arm 481 against the stud 480. When the arm 121 moves downwardly under the influence of the depressed key it rocks the bail 476 and arms 477 and 478 counterclockwise, and, through the spring 479, rocks the arm 481 in the same direction, thrusting upwardly a link 482 held by a spring 483 against an arm 484 secured to a shaft 485 which arm 484 is held against a stop stud 486 by a spring 487. The upper end of the link 482 abuts against an insulating block 488

supported on the lower one of a pair of switch blades carrying contacts 489 (see also Fig. 10 right side of the sheet near the center) closing said contacts.

Closing contacts 489 energizes a bail magnet 490 (Figs. 1, 2, and 10) which operates another bail including arms 491 and 492 (Fig. 4) pivoted on the shaft 122 and connected at their left hand ends (Figs. 1 and 2) by a bail 493. Between them the arms 491 and 492 also carry an armature 494 adapted to be operated by the magnets 490.

Examination of Figs. 1 and 2 discloses that the bail 493 rests just above and in contact with the angular or flanged part of the bail 476. When a key 110 is depressed and arm 121 rocked, the bail 476 moves downwardly away from the bail 493, but energization of magnets 490 rocks the bail 493 downwardly into contact with the now lowered bail 476 to prevent restoration of the latter until magnets 490 are deenergized. The bail 493 is cut away beneath all of the arms 121. Consequently, downward movement of these arms does not affect the bail 493.

The arm 492 (Fig. 2) is integral with an upwardly extending arm 495 and a spring 496 holds this arm and the bail 493 in retracted position until the magnets 490 are energized whereupon the bail 493 and the arm 495 are rocked counterclockwise. At this movement a link 497 pivotally connected to the free end of the arm 495 is drawn toward the left for the purpose of operating an escapement device which permits an amount corresponding in value to the particular key 110 depressed to be set on one of a group of set-up wheels 498 (Figs. 4, 6, and 7).

These wheels are mounted on a shaft 499 supported in the frame plate 32 and in a bracket 500 secured to the frame plate 31 (Fig. 4), and are slidable as a group longitudinally on the shaft 499 toward the left from the position in which they appear in Fig. 4 by means to be described later. In this position (Figs. 4 and 7) the wheel 498 on the extreme left is in mesh with a master set-up wheel 506 secured to a shaft 507 mounted in the frames 31 and 32. Hubbed to the gear 506 is a friction disk 508 which cooperates through the medium of a facing 509 of leather, or other suitable material, with a disc 510 fast to a constantly rotating gear 511. A spring 512 compressed between a hub 513 of an arm 514 on the shaft 507 and a disc 515 provides a constant pressure between the discs 508 and 510 whereby the gear 511 drives the gear 506 when the latter is freed by the above mentioned escapement device.

The gear 511 meshes with a gear 516 secured to a shaft 93 which rotates constantly when the machine is in operation.

Fast on the left hand end of the shaft 507 (Fig. 7) is a gear 517 meshing with a gear 518 on a shaft 519 (see also Fig. 4) on which is also mounted a pin drum 520. The drum 520 has slidably mounted therein a plurality of pins 521 (Figs. 1, 4, and 7) adapted, when thrust toward the right (Fig. 7) to cooperate with an escapement pawl 522 fast on a shaft 523. The upper end of an arm 524 also fast on the shaft 523 (Fig. 2) rests in the path of the lower end of a lever 525, the upper end of which lever 525 rests normally in the left hand end of a recess 526 in the lower side of the link 497.

Depression of a key 110, for instance the "6" key, first closes the corresponding contacts 125 and then, as the depressed key nears the limit of

its downward travel, the link 482 closes the contacts 489 completing a circuit from the line 162 (Fig. 10), wire 190, contacts 125 now closed and corresponding to the particular key depressed, a 5 pin control magnet 521, contacts 528 now closed, contacts 489 now closed, to line 163. A circuit is also completed from wire 190 through a relay magnet 529, contacts 528 normally closed, contacts 489 now closed to line 163. The relay magnet 529 closes its relay contacts 530 so that at substantially the same time contacts 489 are closed a circuit is established from line 162 to the bail magnets 490 and through both contacts 489 and 530 to line 163.

15 Energization of the pin magnet 521 (Fig. 7), in this example the "6" magnet, attracted its armature 536 which acts to thrust the particular pin 521 then in line with said armature toward the right (Fig. 7) into the plane of a nose 537 on 20 the escapement pawl 522. The pin drum 520 is normally prevented from rotating due to the pin 521 previously set-up resting against the nose 537 of the escapement pawl 522. As soon as the selected pin 521 is setup, the pin magnet 521 has 25 accomplished its purpose for the instant operation and may be deenergized. This is effected by the arm 495, which, as it nears the end of its counterclockwise movement, strikes the button or block 542 and opens contacts 528. This also 30 de-energizes magnet 529, opening contacts 530. The bail magnets 490, however, are held energized through the contacts 489, which do not open until the projected pin 521 nears the end of its movement, which movement is limited by the 35 nose 537 of the escapement member 522.

When the bail magnet 490 is energized it rocks the balls 476 and 493 counterclockwise as set forth above and near the end of this stroke the link 497 (Fig. 2) rocks the lever 525 counterclockwise, said lever at the same time rocking the arm 524, shaft 523 and the escapement pawl 522 clockwise removing the nose 537 from the path of the pin 521 then pressing against said nose thus freeing the pin drum 520 and the shaft 45 519 for rotation.

The armature 536 of the several digital pin magnets 521 are spaced differentially away from the nose 537 of the escapement pawl 522 in a counterclockwise direction so that when the pawl 522 is rocked to free the drum 520 said drum and the shaft 519 will rotate a distance a number of steps proportional to the particular key 110 depressed, which in this case is the "6" key when it is again arrested by the projected pin 521 55 striking the pawl 522. This pawl was returned to its former position (Fig. 1) by one of a series of teeth 538 on the drum 520 wiping an ear 539 on the opposite end of the pawl 522 thus rocking said pawl counterclockwise.

60 As the projected pin 521 approaches the nose 537 of the escapement pawl 522 it strikes an arm 560 (Fig. 1) fast on the previously described shaft 485 rocking this shaft and the arm 484 (Fig. 2) counterclockwise. It will be remembered 65 that the spring 483 normally presses the link 482 against the arm 484. The counterclockwise movement of the arm 484 rocks the link 482 also counterclockwise carrying the upper end of said link clear of the block 488 whereupon the contacts 70 498 immediately open, de-energizing magnet 490.

The pin 521 last set up remains effective to hold the drum 520 against rotation until another key is depressed operating the pawl 522. The pin primarily set up is restored just after it passes 75 the nose 537 by a cam face on the end of a

bracket 535 (Fig. 7) projecting from a frame 110.

As the bail 493 (Fig. 2) and the arm 495 near the end of their counterclockwise excursion the link 497 rides onto a stud 541 which rocks said link upwardly clear of the lever 525 which is then 5 permitted to be restored to its normal position as the tooth 538 (Fig. 1) wipes the ear 539 rocking the pawl 522, shaft 523 and arm 524 (Fig. 2) counterclockwise. The link 497 is restored to its 10 normal position when the arm 495 moves clockwise to its normal position.

Obviously the operation of the above described mechanism upon depression of a key 110 effects a partial rotation of the shaft 519 corresponding in degree of rotation to the value of the particular key depressed plus one. Thus if the "0" key is depressed the shaft 519 is rotated one step, the "1" key causes a two-step rotation, etc.

The differential rotation of the shaft 519 is 20 effected by the continuously rotating gear 511 through the friction drive 508—510 as set forth above thus imparting through the master gear 506 (Figs. 7 and 8) and consequently to the particular set-up gear 498 in mesh with the master 25 gear a rotation sufficient to set the gear 498 to a position corresponding to the value of the depressed key 110. Thus, if the "6" key 110 was depressed the wheel 498 then in mesh with the master gear 506 will be rotated seven steps to 30 bring the "6" position on the wheel 498 under a sight opening 543 (Figs. 3 and 8) where it is visible to the operator.

Set-up wheels

35

In setting up a number comprising a plurality of denominational orders on the set-up wheels 498 the operator sets up the highest denominational order first, and then sets up the remaining denominational orders in succession from the highest to the lowest order. Assuming then that the "6" key 110 was depressed to set up the highest denominational order of a number, the set-up wheels 498 (Figs. 4 and 7) are all the way to the right with the left hand one of the wheels 498 in 40 mesh with the master gear 506. As each number is set up the group of wheels 498 are shifted in two movements, one space to the left to bring the left-hand wheel in line with the right hand one of a series of racks 575 and to bring the second 45 wheel 498 into mesh with the master gear in readiness to set the next denominational order digit thereon. The mechanism for shifting the wheels 498 will now be described.

As mentioned above the set-up wheels 498 are 55 slidably mounted on the shaft 499. The group of wheels 498 is embraced by a pair of arms 545 (see Fig. 4) projecting from a sleeve 546 slidably mounted on a shaft 547 supported in the bracket 500 and in the frame 32.

A roller 548 (Fig. 5) carried on the sleeve 546 projects into a spiral cam groove 549 formed about a cylindrical member 550 secured on a shaft 551 rotatably supported in the frame 32 and in a bracket 552 secured to said frame.

In order to rotate the cam 550 a gear 553 secured on the shaft 551 near the frame 32 (Figs. 4 and 5) meshes with a segmental gear 554 pivoted on the shaft 507. Also meshing with the segment 554 is a gear 555 secured to an escapement ratchet 70 556 mounted to rotate on a stud 557 projecting from the frame 32. A spring 558 having one of its ends secured to the arm 514 mounted on the shaft 507 and secured to the segment 554 normally urges the segment 554 counterclockwise and 75

the gear 555 and ratchet 556 clockwise (Fig. 5) but these parts are prevented from rotating due to the cooperation of an escapement pawl 560 loosely mounted on a shaft 566 supported between the frames 31 and 32. The pawl 560 is normally urged clockwise to the position in which it appears in Fig. 5 by a spring 567. Secured to the shaft 566 adjacent the pawl 560 is an arm 568 carrying a stud 569 projecting into a slot 570 in the pawl 560. The bifurcated end of an arm 571 secured on the shaft 566 between the frames 31 and 118 (Figs. 4 and 6) embraces a stud 572 (Figs. 1 and 6) projecting from the bail arm 491 through a clearance opening in the frame 118.

15 It will be recalled that the bail arm 491 is rocked counterclockwise (see Fig. 6) upon energization of the bail magnets 490. This movement is transmitted through the stud 572, arm 571 and shaft 566 to rock the arm 568 (Figs. 5 and 8) counterclockwise. Near the extreme of this movement of the arm 568 the stud 569 (Fig. 5) strikes the left hand end of the slot 570 and rocks the pawl 560 slightly counterclockwise to disengage a hook 573 from the ratchet 556, and, 20 at the same time, moving a nose 574 into the path of the next ratchet tooth.

25 As soon as the nose 574 is clear of the ratchet the spring 558 acting through the segment 554 rotates the gear 555 and the ratchet 556 one-half tooth space. This movement is transmitted by the segment 554 to the gear 553 and the cam 550 (see Fig. 4) rotating the cam sufficiently to displace the sleeve 546 and the group of wheels 498 one-half step toward the left. This movement is not sufficient to carry the particular wheel 498 then in mesh with the master wheel 506 out of engagement therewith.

30 At this point in the operation the master wheel 506 receives its increment of rotation under the control of the depressed key 110, which in the present example is the "6" key, and the pin drum 520, as set forth above, to correspondingly rotate the particular set-up wheel 498 in mesh therewith seven spaces to the "6" position after which the 35 magnets 490 are deenergized by opening of the contacts 489 and the bail arm 491 is restored clockwise to normal.

35 As set forth above, the contacts 489 are opened at the end of the rotation of the pin drum 520, which also is at the end of the operation of the master wheel 506.

40 This rocks the arm 571 (Fig. 6) shaft 566 and arm 568 (Figs. 5 and 8) clockwise to free the escapement pawl 560 to the spring 567, which 45 immediately rocks the pawl in the same direction disengaging the nose 574 from the ratchet 556, and engaging the hook 573 therewith. At this time, and under the influence of spring 558 the segment 554, receives its second movement advancing the ratchet 556 one-half step to complete a full step of movement. Likewise, the frame 545 and spiral cam 550 receives their second clockwise rotation (Fig. 5) to shift the set-up wheel the second half step toward the left. This 50 carries the highest denominational order set-up wheel out of mesh with the master wheel 506, and positions that wheel just above and in a vertical plane with, but not in mesh with the right hand, or lowest denominational order rack of the series of racks 575 (Figs. 4, 6, and 7).

55 The same operation is repeated as each key 110 representing a denominational order of a number being set up is depressed. The set-up wheels 498 being shifted one full step toward the left and

the next succeeding wheel being differentially set according to the particular key 110 depressed.

Set-up wheel aligner

60 In their normal right-hand position (Fig. 4) the set-up wheels 498, with the exception of the highest order wheel, that is, the left-hand wheel, are in engagement with a fixed aligner 561, secured to, and projecting inwardly from the frame 32. This lock is not effective for the highest order wheel 498 as it is in mesh with the master gear 506 ready for a rotation.

65 As the wheels are shifted toward the left (Fig. 4) they are moved successively out of engagement with aligner 561 and into engagement with the master gear 506 to receive their adjustment then out of engagement with the master gear 506 and into engagement with an aligner 562 carried by one arm of a bell crank 563 (Fig. 6) pivoted on the shaft 507. The other arm of the bell crank 20 563 carries a roller 564 cooperating by means of a spring 591 with the cam profile of a box cam 565 fast on a cam shaft 94.

70 At the proper time, after the amount is set on the wheels 498 and after the racks 575 are lifted 25 into mesh with the wheels 498, the cam 565 operates to permit a spring 591 to rock the bell crank 563 clockwise to remove the aligner 562 from engagement with the set-up wheel 498. The racks 575 then move toward the right until the end 30 of a concentric slot 596 in the wheel 498 strikes a stop rod 597 (Fig. 5) carried between the arms 545 and extending through the slots 596 in all of the wheels 498. Thus, the racks 575 receive their differential movement under control of the previously adjusted set-up wheels 498.

75 After the racks 575 are set they are disengaged from the wheels 498, and at the same time the aligner 562 is brought into engagement with the said wheels.

Rack engaging mechanism

80 After the complete number or amount has been set on the wheels 498 the operator depresses a release bar 97 (Fig. 3), which, as will be later described, operates a one-revolution clutch (Fig. 9), to impart one complete counterclockwise rotation to the cam shaft 94. Mechanism is operated by the cam shaft to raise the racks 575 into mesh with the set-up wheels, and then restore said 85 wheels to zero or normal thereby differentially setting the racks 575 a distance corresponding to the setting of the individual wheels 498. The movement of the racks 575 is utilized to actuate the totalizer and to set printing elements, as will 90 be fully described later.

95 The racks 575 are slidably mounted in a frame including plates 576 (Figs. 6 and 8) having their right hand ends pivoted on a stud 577, the racks being slotted at the right to embrace the stud 577. The left hand ends of the plates 576 are joined by a bar 578 (Figs. 4, 6, and 8). This end of the rack frame is adapted to be raised and lowered to bring the racks 575 into and out of mesh with the set-up wheels 498. The frame is guided in its movement by projections 579 (Fig. 4) on a cross bar 580, supported between frames 31 and 32. The racks 575 are slotted near the left hand ends and are slidably mounted on a rod 581 (Fig. 6) extending between the side plates 576 of the rack 70 frame. In its normal position the bar 578 rests on a plate 582 secured to the bottom of the bar 580, and extending beneath the bar 578 (see Fig. 6).

100 The mechanism for raising the racks into mesh 75

with the set-up wheels includes a groove 583 in the box cam 565 (Fig. 6), fastened on the cam shaft 94. This cam is adapted to rock a lever 584 pivoted on a stud 585 projecting from the frame 31. A flattened stud 586 on the left hand end of the lever 584 rests beneath an arm 587 pivoted to one arm 588 of a bell crank 589, mounted on a rod 590. Formed on the end of the arm 587 is a slotted ear 596 surrounding an angular 10 projection 597 on the plate 576 nearest the frame 31. The purpose of this construction will be explained later.

Referring to Fig. 6, it is obvious that rotation of the cam 565 through the groove 583 will rock 15 the lever 584 first clockwise and then counterclockwise to normal. On its clockwise movement the lever 584 by means of stud 586 rocks the arm 587 counterclockwise to raise the rack frame, thus carrying the racks 575 into mesh with the set-up 20 wheel 498.

Set-up wheel restoring

As soon as the aligner 562 is re-engaged with the set-up wheels 498, these wheels are shifted 25 toward the right (Fig. 4) to their normal position by one continuous movement. This is accomplished by rotating the cam 550 and consequently by the cam groove 549 moving the frame 545 backwardly the same distance it was moved to shift 30 the wheels 498 step-by-step as the numbers are set up. As the escapement pawl 560 (Figs. 5 and 8) is operated to permit the spring 558 to rotate the segment 554 in the setting up of numbers, another segment 598 (Fig. 8) pivoted on the shaft 93, and meshing with a segment 599 integral with the segment 554 is correspondingly rocked to carry a roller 600 on an arm 601 integral with the segment 598, into the path of a profile cam 602 fastened on the shaft 94.

Near the end of the rotation of the shaft, the 40 cam 602 rocks the arm 601 and the segment 598 counterclockwise to normal, rocking the segment 554 clockwise to its normal position. This movement of the segment 554 rotates the gear 553 and the cam 550 counterclockwise sliding the 45 sleeve 546 and its group of set-up wheels 498 toward the right to the position in which they appear in Fig. 4.

At this clockwise rotation of the segment 554 the gear 555 and the ratchet 556 are also rotated 50 counterclockwise. This rotation, however, is idle since the escapement pawl 560 vibrates idly, the slot 570 being of sufficient length to permit the pawl to vibrate without displacing the stud 569.

Error key mechanism

Means is also provided to rotate the set-up wheels 498 backwardly to zero in case an erroneous set-up is made thereon. This means includes a restoring rod 603 (Fig. 5), carried between a pair of arms 604 secured on the shaft 499. The rod 603 extends through all of the slots 596 in the wheels 498, and is of sufficient length to permit the longitudinal movement of the group of wheels 498 as they escape to the left (Fig. 4) when being set up. A gear 605 (Fig. 8) secured to the shaft 499 meshes with a segment carried on an arm 606 pivoted on the shaft 93 and forming one arm of a lever. The other arm 607 of the lever carries a roller 608 projected into a cam groove 609 in a cam 610 secured to the cam shaft 94.

The cam 610 operates to rock the lever 606—607 clockwise, which rotates the gear 605, shaft 499, 70 and the restoring rod 603 counterclockwise to re-

store the wheels 498 to normal. On normal operation the wheels 498 are restored as the racks 575 advance toward the right, the restoring rod 603 following this movement, to insure that all of the set-up wheels 498 are fully restored in case of 5 failure.

However, on operations wherein an erroneous number has been set up on the wheels, the operator presses the error key 128 which will be described later, renders the rack engaging mechanism ineffective, so that the set-up wheels 498 will not be restored by the racks 575 as they move toward the right. In this case, operation of the restoring rod 603 (Fig. 5) effects the complete restoration of the set-up wheels 498, to their normal position. 10 15

Locking devices for actuating racks

A number to be set on the set-up wheels 498 may vary in the number of denominational orders 20 from one to nine, the numbers being limited in denominational order to the numbers of the set-up wheels 498 provided in the machine. In the illustrated embodiment, nine of these wheels are provided, however, when a number is set on these 25 wheels utilizing less than the nine wheels, certain of the racks 575 will not cooperate with the wheels 498, in which case it is necessary to provide means to prevent such racks as do not mesh with the set-up wheels 498 from movement toward the right. 30

This means includes a series of pawls 611 (Figs. 4 and 6) there being a pawl 611 cooperating with each rack 575. The pawls 611 are pivoted on a rod 612, mounted in a bracket 613 carried on ears 614 bent inwardly from the upper edge of the 35 side plates 576 of the rack frame, (see Fig. 6). Referring to Fig. 6, it can be seen that the pawls 611 rest in the paths of projections 615 on the left hand ends of the racks 575. As the group of set-up wheels 498 escape toward the left (Fig. 40 7) a projection 616 on the sleeve 546 positions itself over tails 617 projecting from pawls 611. When the rack frame 576 is brought upwardly to mesh the racks 575 with the set-up wheels 498, the 45 tails 617 of the pawls 611 move upward therewith, and the projection 616 rocks the pawls clockwise about pivot 612 to remove the pawls from cooperative relationship with the projections 615 on the racks 575.

Obviously only those pawls 611 will be rocked 50 which lie beneath the projection 616. Thus, if a number comprising four denominational orders is set on the wheels 498, the left hand four of these wheels (Fig. 4) will engage the right hand four of the rack 575. Likewise the projection 616 55 will move left over the four pawls 611 to the right. Now when the rack frame 576 is rocked upwardly (Fig. 6) the four pawls to the right will be rocked out of engagement with their respective racks, whereas the remaining pawls 611 60 cooperating with higher denominational order racks 575 will remain in their position wherein they are effective to restrain the racks 575 from moving toward the right (see Fig. 6) to set the printing type elements to be described later. 65

It was stated above that after an amount was set on a set-up wheel 498, and before the release bar 97 (Fig. 9) is pressed to operate the machine, the operator may observe the amount set on the wheels 498 through the sight opening 543 (Fig. 8). 70 If the amount set thereon does not correspond to the amount desired to be entered, the operator may, by pressing the error key 128, (Fig. 6) erase the setup from the wheels 498 without entering the amount into a totalizer or printing the amount 75

on the record materials. This is accomplished by preventing the engagement of the racks 575 with the set-up wheels 498, and operating the machine through the regular cycle. This error correcting operation is effected by the depressing of the error key 128 (Fig. 6) which is mounted on a lever 618. The lever 618 is bent, as illustrated at 619, and is pivoted on a stud 620 supported in a projection 621 (Fig. 4) on the cross bar 580.

10 A link 622 (Fig. 6) connects the lever 618 to the arm 583 of the bell crank 589 so that when the error key 128 is depressed rocking the lever 618 counterclockwise, the link 622 rocks the bell crank 589 likewise counterclockwise. This 15 thrusts the link 587 toward the right, moving the end of the link out of cooperation with the stud 586 in the lever 584. Now when the cam groove 583 (Fig. 6) rocks the lever 584 clockwise the stud 586 carried by the arm 584 rocks idly without 20 moving the link 587, or transmitting the movement of the rack frame. The other arm 627 of the bell crank 589 carries an ear 628 which cooperates with a shoulder on a detent 629 to hold the key depressed during the operation.

25 Depression of the error key 128 also operates the release bar 97 in the following described manner: An arm 623 rigidly connected to the bell crank 589 (Fig. 6) but spaced apart therefrom on the shaft 590 rests immediately above the stud 310 on the release bar (see also Fig. 9) so that when the bell crank 589 is rocked counterclockwise by depression of the error key 128, the arm 623 acting on the stud 310 moves the release bar 97 downwardly to release the machine for an 35 adding cycle. As just explained, the racks 575 are not raised into engagement with the set-up wheels 498 on this operation, also these racks are not shifted toward the right, due to the pawls 611 remaining in engagement with the projection 616.

40 However, the segment 554 (Figs. 5 and 8) is given its restoring movement to rotate the cam 550, thus restoring the wheels 498 in one stroke to their normal right hand position, as viewed in Fig. 4. Likewise the cam groove 609 (Fig. 8) 45 operates the arm 606 to rotate the gear 605, which in turn operates the restoring rod 603 (Fig. 5) to rotate the set-up wheels 498 counterclockwise to their normal positions.

Rack operating mechanism

50 Referring to Fig. 8 each of the racks 575 carries a stud 628 at its right hand end which stud is embraced by the bifurcated end of an arm 625 of a bell crank 631 pivoted on a shaft 632. The 55 other arm 633 (Fig. 11) of the bell crank 631 is also bifurcated and straddles a stud 634 carried by a vertically disposed rack 635. There is a bell crank 631 and vertical rack 635 for each denominational order rack 575.

60 At its upper end the vertical rack 635 carries type elements 636 slidably mounted therein; and 65 slidably mounted on the rack 635 are totalizer actuators 637. The purpose of the bell crank 631 is to transmit the movement of the rack 575 to the vertical rack 635, for the purpose of positioning the type element 636 differentially, and for actuating the totalizer 676 to enter the amount set up on the keys 110.

The arms 625 of the bell crank are normally 70 abutting a bail 640 carried between a pair of arms 641 (Figs. 8 and 11) secured to the shaft 632, by a spring 642 stretched between a projection 643 (Fig. 8) on the lower side of the rack 575 and one of the rods 644 carried between the arms 641.

75 After the racks 575 have been rocked into en-

gagement with the previously set set-up wheels 498, the bail 640 (Fig. 8) receives an invariable excursion, first counterclockwise and then clockwise to normal. On its counterclockwise travel, the rod 644 acting through the spring 642 draws 5 the racks 575 which were engaged with the set-up wheels toward the right therewith, each rack 575 being differently stopped by its corresponding set-up wheel 498, engaging the stop rod 597 (Fig. 5). The rod 644 continues its invariable excursion after the racks 575 are arrested merely stretching the springs 642.

10 After the racks 575 are disengaged from the set-up wheels 498, as described above, the bail 640 receives its clockwise or restoring movement to 15 shift the racks 575 leftward to their normal position.

The means for operating the bail 640 is illustrated in Fig. 8, and includes a pair of complementary cams 645 fast on the shaft 94 cooperating with rollers carried on a curved arm 646 pivotally supported on a rod 638. A link 647 connects the curved arm 646 with an arm 648 secured to the shaft 632. At each adding cycle the cams 645 (Fig. 8) rock the arm 646 first clockwise and through the link 647 rock the arm 648, shaft 632, and the bail 640 counterclockwise. The cams 645 then reverse this movement rocking the arm 646 counterclockwise and through the link 647 rock the arm 648, the shaft 632 and the bail 640 clockwise to restore the racks 575 to their normal position.

Totalizers and printing mechanism

It was stated above that each of the racks 635 (Fig. 11) are shifted vertically a distance commensurate with the movement of the rack 575 under the control of the related set-up wheel 498. This movement positions the corresponding type element 636 opposite a platen 649. Mechanism is 40 then operated to cause hammers 716 to force the type element 636 against the record material in order to take the impression therefrom. This type of printing mechanism is well known and is fully described in the parent application. 45

When the racks 635 (Fig. 11) are in their differentially raised positions, the totalizer 676 is moved into mesh with the racks 637 and when the racks 637 are lowered the item is entered in the totalizer 676. The totalizer engaging means 50 is fully described in the parent application.

Release bar

Immediately after depressing the keys 110 the operator depresses the release bar 97 rendering 55 a one revolution clutch (Fig. 9) effective to impart one complete counterclockwise rotation to the cam shaft 94 in the following described manner:

As is fully described in the parent application 60 the machine is provided with a motor 40 (Fig. 10) which runs continually as long as a switch 159 is closed when the machine is in operation. The motor drives the shaft 93 continually while the machine is in operation and 65 drives the main cam shaft 94 by means of a gear 95 (Fig. 9) fast on the drive shaft 93 meshing with a larger gear 96 rotatably mounted on the cam shaft 94. A one revolution clutch is provided and is rendered effective under control of 70 the release bar 97 to couple the cam shaft 94 to the gear 96 whereby the shaft 94 receives one complete counterclockwise (Fig. 9) rotation at each adding cycle. This clutch and release bar 75 will now be described.

The bar 97 is mounted on a stem 308 which is slidably supported by a pair of headed screws 309 projecting from the frame 31. The stem 308 carries a stud 310 which is embraced by the bifurcated end of one arm of a bell crank 311 having its other arm connected by a link 312 to a lever 313 pivotally supported on the frame 31. Depression of the release bar 97 rocks the bell crank 311 clockwise drawing the link 312 leftward (Fig. 11) thus rocking the lever 313 also clockwise. This raises a link 314 depending from one arm of the lever 313. The link 314 has a shouldered notch in one edge thereof normally held by a spring 315 in cooperative relation with a stud 316 projecting from a retaining pawl 317 pivoted concentrically with the lever 313.

The pawl 317 cooperates with the tail of a drive pawl 318, pivotally carried on a disc 319 secured to the cam shaft 94, to hold said pawl 318 out of engagement with a drive ratchet 320 secured to the gear 96 and constantly rotated thereby in a counterclockwise direction (Fig. 9).

The clockwise movement of the lever 313, imparted thereto by depression of the release bar 97, as above stated, raised the link 314 which, due to the stud 316, rocks the retaining pawl 317 clockwise against the tension of its spring 326, freeing the drive pawl 318 to the action of its spring 327 which immediately rocks the pawl 318 into engagement with the ratchet 320. The disc 319 is now rotated counterclockwise one complete rotation.

Shortly after the disc commences its rotation a block 328 secured to the side thereof strikes the lower end of the link 314 and rocks the link clockwise to free the pawl 317 to its spring 326 which rocks said pawl counterclockwise against a stop stud 329. Near the end of the rotation of the disc 319 and of the shaft 94 to which it is fast, the tail of the drive pawl 318 strikes the pawl 317, rocking the drive pawl 318 out of engagement with the ratchet 320 to stop rotation of the shaft 94. A spring-pressed pawl 330 cooperates with a notch in the periphery of the disc 319 to prevent retrograde movement of the shaft 94.

Key release key

It will be recalled that the error key 128 when depressed is latched down by the detent 629 (Fig. 6). To release the key a special key 131 (Fig. 12) is provided which functions to release the key 128 by shifting the detent 629 to ineffective position.

The key release key 131 is pivoted on the rod 590 (Fig. 12) and is operated against the tension of a spring 1225. The key has pivoted thereto a link 1230 having a slot 1231 receiving a pin 1232 carried by an arm 1233 secured to one arm of a bail 1188 against which the detent 629 is spring-pressed. When the key 131 is depressed the link 1230 is elevated raising the free end of arm 1233 and rocking bail 1188 counterclockwise to rock the latch 629 and thus releases the error key 128.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

75 What is claimed is as follows:

1. In a machine of the class described, in combination, a series of digit wheels, a single master wheel for setting said digit wheels seriatim, an escapement mechanism for controlling the operative relationship between said master wheel and said series of digit wheels, a rotatable drum for controlling the differential movement of said master wheel and having a series of digit determining members, a movable stop normally cooperating with the member previously rendered operative, a series of ten keys, a series of magnets for shifting said members, an electrical circuit for each of said magnets and controlled by the related key, an electro-magnet adapted to shift said stop to release said drum for rotation, means whereby said electro-magnet operates said escapement mechanism, and an electrical circuit for said electro-magnet including controlling contacts closed by the depression of any key to energize said electro-magnet. 21

2. In a machine of the class described, in combination, a series of digit wheels, a series of ten keys, a master wheel, means for preventing rotation of said master wheel, a digit setting mechanism for determining the differential rotation of said master wheel comprising a series of digit stops, electro-magnets for shifting said stops, circuits for said magnets including key controlled contacts, an electro-magnet, a member operable by any one of said keys and adapted to close a set of contacts to energize an electro-magnet in electrical series therewith, an operating member operated by the last named electro-magnet, for releasing the master wheel for rotation, an escapement mechanism for controlling the operative relationship between the digit wheels and the master wheel, and means whereby said operating member causes the operation of the escapement mechanism when said electro-magnet is energized. 30

3. The combination with a series of ten keys, of a series of digit wheels, a master wheel for setting said digit wheels differentially, digit electrical circuits closed by said keys, a normally locked digit setup mechanism controlling said master wheel and including shiftable digit stops, a series of electrical means for shifting said stops controlled by said circuits, an arresting member engaging the previously shifted digit stop, an electro-magnet, an electrical circuit therefor closed by the depression of any key, means whereby said electro-magnet causes the movement of said arresting member to release the digit set-up mechanism, means whereby said electro-magnet controls the operative relationship of said digit wheels and said master wheel, and means whereby the electro-magnet opens its electrical circuit. 50

4. The combination with a series of ten keys, of a series of digit wheels, a master wheel for setting said digit wheels, a power drive, a friction drive between said master wheel and said power drive, a digit-set-up mechanism rotatable with said master wheel and including digit stops set by said keys, an arresting member engaging the previously shifted digit stop to prevent rotation of said master wheel by the power drive through said friction drive, an electrically operated means set in operation by the initial depression of a key for shifting said arresting member, and means whereby said electrically operated means changes the operative relationship between said master wheel and said digit wheels. 60

5. In a machine of the class described, the combination with a series of item wheels, of a series of keys depressed manually, of means for 75

differentially setting said wheels, a series of electro-magnetic means for controlling the differential operation of said setting means and each in a related digit electrical circuit, key controlled contacts, one in each digit electrical circuit for selecting the related digit electrical circuit, a set of contacts closed by any depressed key to cause closure of the selected digit electrical circuit and automatically opened after the depression of a key, and means for causing the opening of the selected digit electrical circuit before said set of contacts automatically open.

6. In an adding machine, a set of ten keys, a set of digit wheels, a master gear for setting said digit wheels, a digit set-up controlling mechanism for said master gear comprising a drum with a series of shiftable digit stops, a plurality of electro-magnetic means controlled by said keys for shifting said stops, a drum arresting member normally engageable with the previously shifted digit stop, electro-magnetically operated means, means whereby the electro-magnetically operated means shifts said drum arresting member to release the drum for rotation, means carried by said drum to thereafter restore the drum arresting member to a position to engage the digit stop shifted by the depression of a key, an electrical circuit including a set of contacts closed by the depression of any key to cause an operation of the electro-magnetically operated means, and means whereby the digit stop shifted by a depressed key causes the opening of the set of contacts.

7. In an adding machine, a series of keys, a series of digit wheels, a master wheel to turn said digit wheels, a continually revolving motor shaft having frictional means connected to said master wheel to turn said master wheel, a normally locked evaluating mechanism movable differentially for controlling the rotation of said master wheel, an escapement means to control the operative relationship of said master wheel and said digit wheels, a series of electro-magnetic means controlled by the keys for determining the extent of movement of said evaluating mechanism, an electro-magnet, electrical means including contacts closed by any key for causing the electro-magnet to be energized upon the operation of any key, means whereby said electro-magnet releases the evaluating mechanism for movement and causes the operation of the escapement means, and means for opening said contacts.

8. In an adding machine, a series of keys, a series of digit wheels, a differentially rotatable master wheel for setting said digit wheels, an escapement means for controlling the operative relationship of said master wheel and said digit wheels, an electro-magnet for causing the operation of said escapement means, an electrical circuit for said electro-magnet, contacts closed upon the initial operation of any key to close said electrical circuit and thereafter automatically opened, a relay magnet, an electrical circuit therefor including normally closed contacts, said electrical circuit being closed by the first named contacts, relay contacts closed when the relay magnet is energized to provide a shunt for the first named contacts, and means whereby said electro-magnet opens the normally closed contacts to open the circuit of the relay magnet to cause its deenergization.

9. In an adding machine, the combination with a series of digit wheels, of a driving shaft, a series of keys, a master wheel for setting said digit wheels frictionally driven by said driving shaft,

normally locked means for controlling the rotation of said master wheel, settable digit stops carried by said means, a plurality of electro-magnetic means for shifting said stops, digit electrical circuits for said electro-magnetic means, contacts controlled by said keys for closing said circuits to cause the related magnetic means to shift an associated stop, electro-magnetic means energized by the operation of any key for releasing said controlling means, an escapement means controlling the operative relationship between said master wheel and said digit wheels, a circuit for said electro-magnetic means, contacts controlled by any of said keys and closed to energize the electro-magnetic means, and means whereby the electro-magnetic means causes the opening of the digit electrical circuits.

10. In a ten-key adding machine, a series of ten digit keys, a series of digit wheels, a master wheel for successively rotating said digit wheels, a master wheel rotation controlling device comprising a drum carrying settable digit stops shifted under control of said keys, a continually rotating driving shaft having a frictional driving connection with said drum, locking means engageable with a previously shifted digit stop for normally locking said drum to prevent rotation of said master wheel, means operated by the depression of a key for shifting said locking means out of engagement with the previously shifted digit stop, means on said drum to shift said locking means to engage with the next digit stop shifted by the depression of a key, and a camming means stationary with respect to said drum for camming the previously shifted stop to an inoperative position.

11. In a machine of the class described, a series of digit wheels, a digit wheel setting device comprising a rotary drum carrying a plurality of shiftable digit stops, a stop member for normally arresting said drum against rotation by engagement with a previously shifted stop, a series of depressible keys for shifting said digit stops, means operated by the depression of any key for shifting said stop member out of engagement with a previously shifted digit stop, means carried by the drum to cause said stop member during the rotation of the drum to be shifted to engage the next digit stop shifted by a depressed key, a camming device engaging the shifted digit stop for returning it to an inoperative position after it has functioned to stop the rotation of the drum, an escapement means for said digit wheels, an electro-magnet energized upon the depression of any key for operating said escapement means, and means whereby a shifted digit stop controls an electrical circuit for said electro-magnet.

12. In a machine of the class described, in combination, a series of digit wheels, a series of keys, operating racks, means for setting said digit wheels, a power drive, means under control of said keys for causing differential rotation of said setting means by said power drive to successively set up said digit wheels, a pair of transverse rods passing through arcuate slots in said digit wheels, means operated by said power drive for resiliently shifting said operating racks under control of said digit wheels as the latter are restored to normal to positions determined by engagement of one of the transverse rods with certain closed ends of the arcuate slots, and means for causing the movement of the other transverse rod to engage with other closed ends of the slots as

- said digit wheels are restored to normal to insure the differential setting of said operating racks.
13. In a machine of the class described, in combination, a set of keys, a power drive, a plurality of rotatable digit representing wheels, means operated by said power drive and under control of said keys for setting up said digit representing wheels, a series of operating racks normally out of engagement with said digit wheels when the latter are being set up, a transverse rod in engagement with closed arcuate slots of the digit wheels, means operated by said power drive to engage the digit wheels with the operating racks, resilient means operated by the power drive for then moving the racks until the digit wheels are rotated to a home position, and means operated by the power drive to move said rod and by its engagement with the closed ends of the slots assist the resilient means to rotate said digit wheels to home position.
14. In a machine of the class described, in combination, a series of digit wheels, means for setting said digit wheels to represent an amount, operating racks, a stationary transverse rod passing through arcuate slots in said digit wheels, a supplemental movable transverse rod also passing through said arcuate slots, resiliently-operated means operated by the power drive to move said operating racks to restore said digit wheels to normal and differentially set said operating racks limited by the engagement of the ends of the arcuate slots with the first-named rod, and an error correcting mechanism having connections for causing the movement of the movable transverse rod to restore the digit wheels to normal without setting said operating racks.
15. In a machine of the class described, in combination, a set of digit wheels, operating racks adapted to be engaged with the differentially set digit wheels, a movable transverse rod in engagement with arcuate slots of said digit wheels,

means for resiliently shifting said racks while engaged with the digit wheels to differential positions, means for concurrently moving said rod to insure the complete differential setting of said racks, an error key, and connections whereby the latter causes the movement of said rod to restore the digit wheels without differentially setting said racks.

16. In a machine of the class described, in combination, a set of digit wheels adapted to be differentially set, a set of operating racks, a power drive, means effective when the digit wheels have been set and operated by said power drive for causing said set of racks to engage with the digit wheels, means whereby said power drive then resiliently moves said racks to differential positions determined by the setting of the digits wheels, means engageable with the wheels and operated by the power drive to restore the digit wheels, an error key depressible upon visually noting an error in the setting of the digit wheels, and means whereby the error key renders the first named means ineffective to prevent an engagement of the set of racks with the set of differentially set digit wheels but causes the operation of the means engageable with the wheels to restore the digit wheels.

17. In a machine of the class described, in combination, a series of digit wheels, a series of keys, means under control of said keys for setting up said digit wheels, operating racks, a frame for shifting said racks to engage with the digit wheels which are set up, elements for normally locking all of said racks, and means shiftable in accordance with the number of digit wheels set up and operated by said frame to cause certain of said elements to be operated to unlock the racks engageable with the digit wheels which have been set up.

FREDERICK L. FULLER. 40
SAMUEL BRAND.
